UNITED STATES PATENT OFFICE

RAYMOND G. MOORE, OF BRIDGEPORT, AND FRANK P. SARGENT, OF STRATFORD, CONNECTICUT, ASSIGNORS TO THE BASSICK COMPANY, OF BRIDGEPORT, CONNECTICUT, A CORPORATION OF CONNECTICUT

DESIGN FOR A HANDLE FOR AUTOMOBILE HOOD CATCH

Application filed August 15, 1928. Serial No. 27,824. Term of patent 14 years.

To all whom it may concern:

Be it known that we, RAYMOND G. MOORE and FRANK P. SARGENT, citizens of the United States, and residents of Bridgeport and Stratford, respectively, in the county of Fairfield and State of Connecticut, have invented a new, original, and ornamental Design for a Handle for Automobile Hood Catch, of which the following is a specification, reference being had to the accompanying drawings, forming part thereof.

In the drawings:—

Fig. 1 is a side elevation of a handle for

automobile hood catch, showing our new design, the hood catch barrel being shown in dotted lines;

Fig. 2 is an inner end elevation; and

Fig. 3 is an outer end elevation.

We claim:—

The ornamental design for a handle for automobile hood catch, as shown.

Signed at Bridgeport, in the county of Fairfield, and State of Connecticut, this 25th day of July, 1928.

RAYMOND G. MOORE.
FRANK P. SARGENT.
